UNITED STATES PATENT OFFICE.

GEORGE O. BAKER, OF SELMA, ALABAMA.

OIL-PRESS MAT.

SPECIFICATION forming part of Letters Patent No. 248,386, dated October 18, 1881.

Application filed August 16, 1881. (Model.)

To all whom it may concern:

Be it known that I, GEORGE O. BAKER, of Selma, in the county of Dallas, in the State of Alabama, have invented a new and useful Improvement in Oil-Press Mats, of which the following is a full, clear, and exact description.

The object of my invention is to furnish oil-press mats of inexpensive, durable, and effective character, by which one or more cakes can be pressed at once in the one mat, and which shall allow free escape of the oil.

The invention consists in the combination, with the hinged leaves or aprons, of the mat of wire cloth or netting, as hereinafter described and claimed.

In the accompanying drawings, Figure 1 is a face view, in an open position, of an oil-press mat containing my improvements. Fig. 2 is a longitudinal section of the mat in a partially closed position, and Fig. 3 is a cross-section of the mat closed.

Similar letters of reference indicate corresponding parts.

A A are the outer leaves of the mat, connected by the hinge-piece *a*, of duck or other flexible material; and B is the middle leaf or apron, attached by a loop, *b*, to the hinge *a*, which loop serves also as a handle by which the mat can be held. The hinge-piece being flexible, and the middle leaf or apron movable on the piece *a*, the leaves have perfect freedom and independence of movement. The outer leaves, A, are formed of wood or other inflexible material, faced on the inner surface with wire cloth or netting *c*, of suitable size of wire and mesh. The edges of the wire-cloth *c* should a selvage, or they may be, as shown, covered by strips *d*, of metal, turned up on the edges. The wire-cloth is attached by pins or rivets or wire driven through the strips *d* and wood backing, or in any suitable manner whereby the clothing is held securely. At the side edges of the leaves A are secured cords or strips *e*, of hair or other suitable material which will allow free escape of oil.

The middle leaf or apron, B, is formed of

wire-cloth, similar to that with which the leaves A are faced, and bound in the same manner with metal strips *f* at the edges. This forms a stiff but elastic leaf, through which the oil can freely pass or escape. There may be additional middle leaves or aprons formed of wire-cloth or other foraminous material used with the mat, so that two, three, or more cakes may be pressed at once.

In using this mat the meal or seed bags are placed between the leaves or aprons in the usual manner. As soon as pressure is applied the wire-cloth takes hold by its meshes on the bags, thus effectually holding the bags in place and preventing them from moving in any direction, while at the same time insuring the even distribution of the seed or meal. The wire-cloth also allows free escape of the oil from the bags and out of the mats.

This mat can be readily and cheaply manufactured, and possesses great strength and elasticity. The wooden backs soften the blows of the pump on the mats, and thus preserve them from the rapid wear that occurs when they are made of hard and non-elastic material, such as metal.

I am aware that an oil-press mat constructed of three leaves hinged together is not new, and also that wire-cloth, in connection with fibrous material, has been used in the construction of oil-press mats; and I therefore do not claim the use of wire-cloth, broadly; but

What I claim, and desire to secure by Letters Patent, is—

In an oil-press mat, the combination, with the outer wooden leaves, A, lined with wire-cloth and connected by flexible joint *a*, of the middle leaf or leaves, B, of wire-cloth, secured to flexible joint *a*, whereby the meal-bags are prevented from slipping and the expressed oil allowed to escape, substantially as shown and described.

GEORGE O. BAKER.
